US00D618680S

(12) **United States Design Patent**
Marchand et al.

(10) **Patent No.:** **US D618,680 S**
(45) **Date of Patent:** **** Jun. 29, 2010**

(54) **MEDIA ENHANCEMENT PERIPHERAL FOR A COMPUTER**

(75) Inventors: **Nicholas Stephen Marchand**, Singapore (SG); **Kar Choon Ng**, Singapore (SG); **Choy Hon Fred Ng**, Singapore (SG)

(73) Assignee: **Creative Technology Ltd**, Singapore (SG)

(**) Term: **14 Years**

(21) Appl. No.: **29/328,598**

(22) Filed: **Nov. 26, 2008**

(51) **LOC (9) Cl.** **14-02**

(52) **U.S. Cl.** **D14/357**

(58) **Field of Classification Search** **D14/137, D14/167, 168, 230, 231, 233, 235, 237, 240–242, D14/299, 432, 435, 436, 155, 496, 300, 301, D14/313, 314, 214, 348–363, 365–370; D18/56; D13/149, 162, 184, 199; D3/201, 273; D10/65, D10/75, 78; 312/223.1, 223.2; 369/34.01, 369/36.01, 272.1; 360/132, 133, 135; 361/679.31–679.45**
See application file for complete search history.

(57) **CLAIM**

The ornamental design for a media enhancement peripheral for a computer, substantially as shown and described.

DESCRIPTION

FIG. 1 is a front, top, left, perspective view of the media enhancement peripheral for a computer in accordance with the present design;

FIG. 2 is a back, bottom, right, perspective view of the media enhancement peripheral for a computer in accordance with the present design;

FIG. 3 is a front view of the media enhancement peripheral for a computer shown in FIG. 1;

FIG. 4 is a back view of the media enhancement peripheral for a computer shown in FIG. 1;

FIG. 5 is a left view of the media enhancement peripheral for a computer shown in FIG. 1;

FIG. 6 is a right view of the media enhancement peripheral for a computer shown in FIG. 1;

FIG. 7 is a top view of the media enhancement peripheral for a computer shown in FIG. 1; and,

FIG. 8 is a bottom view of the media enhancement peripheral for a computer shown in FIG. 1.

The broken lines shown are for the purpose of illustrating unclaimed portions and form no part of the claimed design.
